UNITED STATES PATENT OFFICE.

HARRY D. SPARLING, OF WALDEN, NEW YORK.

COUNTERSINK-GAGE.

1,389,390.

Specification of Letters Patent. Patented Aug. 30, 1921.

Application filed July 25, 1919. Serial No. 313,334.

To all whom it may concern:

Be it known that HARRY D. SPARLING, a citizen of the United States, residing at Walden, in the county of Orange and State 5 of New York, has invented new and useful Improvements in Countersink-Gages, of which the following is a specification.

The object of the invention is to provide means for use in conjunction with countersinks to prescribe the depth to which the countersink may enter a hole. The device thus provides for the countersinking of all holes a specified depth so that rivets or screws that may be inserted through the 15 holes may leave their heads flush with the surface of the plate or the stock through which they may pass. The device is particularly serviceable in ship work in which at the present time the countersinking is done 20 without any means for gaging the depth to which the countersink enters. Thus some holes are countersunk deeply while others are left shallow and in order that riveted work may be flush with the surface of the 25 plate, it is sometimes necessary to chip off the rivet where it projects beyond the surface due to the hole not being countersunk a sufficient depth.

A further object of the invention is to provide means for the adjustment of the gaging, so that the depth to which the countersink may work may be varied.

Other and further objects appear in the following description wherein the invention 35 is set forth in detail.

To the exact construction in which the invention is shown and described, it is not to be restricted. The right is reserved to make such changes or alterations as the actual reduction to practice may suggest, in so far as such changes or alterations are compatible in spirit with the annexed claim.

In the accompanying drawings:

Figure 1 is a view in side elevation of a 45 countersink equipped with the improved device.

Fig. 2 is a view similar to Fig. 1 but showing the gage in section.

Fig. 3 is a plan view of a clip used to 50 retain the gage in position.

As shown, the invention is applied in conjunction with the usual form of countersink 1 provided with the usual shank 2 for hold-

ing the same in appropriate rotating means. To provide for the attachment of the improved gage, a peripheral slot 3 is formed in the body of the countersink. The gage comprises a cylindrical member 4 formed with a frusto conical end 5 and this gage is dimensioned to slide over the body of the 55 countersink and to allow the nose of the countersink to project through the smaller base of the frusto conical end 5. The gage may be moved longitudinally with respect to the body of the countersink to provide for 60 various degrees of expansion of the nose through the opening end of the gage and to this end there are provided a plurality of perforations 6 formed in the cylindrical portion 4 on diametrically opposite sides, each 65 hole 6 being opposite a corresponding hole on the opposite side of the cylindrical portion. A spring clip 7 embraces the cylindrical portion and is formed with two in-turned teats or lugs 8 which pass through any 70 pair of holes 6 to have their ends engage in the slot 3. The clip is attached or detached by springing these opposite ends apart to disengage the teats from the holes 6 and these teats may then be engaged in another 75 pair of holes, the degree to which the nose of the countersink projects through the open end of the gage being determined by the 80 holes 6 which the teats 8 engage. Thus the device can be set so that the lower end of the 85 gage will abut the work when the nose has penetrated the work a specified distance and at this point further penetration of the countersink is precluded.

The invention having been described, what 90 is claimed as new and useful is:

The combination with a countersink, having a peripheral slot formed therearound, of a gage member in surrounding relation to the countersink, the gage member being formed 95 with a plurality of holes on diametrically opposite sides formed at varying distances from the working edge, the oppositely disposed holes being arranged in pairs, and a clip member embracing the gage and having 100 teats or lugs formed on its ends, which teats or lugs enter the holes and engage in said slot for the purpose specified.

In testimony whereof he affixes his signature.

HARRY D. SPARLING.
